UNITED STATES PATENT OFFICE

NATHANIEL G. HOLLAND, OF NORFOLK, VIRGINIA, ASSIGNOR TO OLD DOMINION MARINE RAILWAY CORPORATION, OF NORFOLK, VIRGINIA, A CORPORATION OF VIRGINIA

HEATING FURNACE

Application filed February 18, 1931. Serial No. 516,745.

The invention relates to a furnace construction, especially designed for heating dwellings or other edifices or enclosures.

An aim of the present invention is to provide a furnace construction, wherein the parts thereof are so formed as to permit easy assemblage and portability for ready transit prior to installation, while the furnace, when installed will operate with minimum fuel consumption and resultant maximum heating qualities in water or steam heating systems, the parts being readily erected and knocked down with dispatch.

Another aim of the invention is to provide a furnace construction, wherein the coils for the circulation of the fluid are arranged in a novel manner for quick heating of the fluid.

A further aim of the invention is the provision of a furnace construction of the character specified which is comparatively simple, thoroughly reliable and efficient in its operation, compact and inexpensive to manufacture.

With the foregoing and other objects in view, the invention consists in the features of construction, combination and arrangement of parts, as will be hereinafter more fully described, illustrated in the accompanying drawings which disclose the preferred embodiment of the invention, and pointed out in the claims hereunto appended.

In the accompanying drawings:—

Figure 1 is an elevation of a furnace constructed in accordance with the invention, portion thereof being broken away to illustrate the internal organization.

Figure 2 is a side view, the casing being broken away.

Figure 3 is a sectional view on the line 3—3 of Figure 1.

Similar reference characters indicate corresponding parts throughout the several views in the drawings.

Referring to the drawings in detail, the furnace comprises a lower burner body 5 molded or casted to present solid opposite ends 6, these being in the nature of vertical walls and a back 7, the upper portion of the body 5 being formed with a horizontal ledge 8 which, at the front thereof and also the

end 6, has bolted or otherwise secured thereto the front section 9 equipped with a swinging door 10 so that access may be had to the fire chamber 11 within this body 5. Extended through the back 7 into the chamber 11 is a burner 12 of any approved type and which receives its fuel from any suitable source of supply.

Superposed relative to the body 5 is an upper housing including the end plates 13, front and back plates 14 and 15 and the top plate 16, the end plates at their rear and forward edges being outturned to provide abutment flanges 17 for the front and rear plates 14 and 15, these being made fast to said flanges 17 by fasteners 18. Likewise, the top plate 16 is provided with marginal flanges 19 for the ends, front and rear plates which are made fast thereto by fasteners 20. These plates at their inner faces are covered by asbestos 21 and at their lower ends are anchored upon the body 5 in any suitable manner within a rim 22 on the latter at the upper portion thereof.

Within the combustion chamber 23 formed by the housing is a fluid circulating unit of the furnace which includes spaced lower cylindrical drums 24, these having centrally of their ends anchoring studs 25 which pass through suitable companion openings in the front and rear plates 14 and 15 and are fitted with nuts 26 which make fast the said drums thereto, it being intended that the drums rest upon the ledge 8 on the body 5. These drums 24, between their ends, are joined together through the medium of cross pipes 27, the latter and the drums being formed with coupling nipples 28 for detachable connection therewith of upwardly directed pipes 29 and 30, these through the medium of coupling nipples 31 communicating with a superposed comparatively large head drum 32 arranged in the upper portion of the housing, the ends of this drum 32 being provided with studs 33 which pass through suitable openings in the front and rear plates 14 and 15 and carry nuts 34 for the anchoring of said studs therein.

Detachably coupled with nipples 35 rising from the drums 24 is a series of coils 36, these

being coupled through the medium of nipples 37 with the drum 32, the coils being disposed in upwardly convergent relation to each other at opposite sides of the longitudinal center 5 of the housing, and likewise the upstanding portions of the pipes 29 converge upwardly within said housing.

Bridging the drum 32 are saddle straps 38 constituting hangers for horizontally disposed perforated baffles 39, these being located on opposite sides of the drum 32 above the coils 36 of the fluid circulating unit, while leading from the drum 32 through the top plate 16 of the housing is a fluid distributing 15 main 40 and adapted to be connected to the top plate 16 for communication with the chamber 23 is a spent products of combustion outlet 41 for a stack for the furnace.

The drums 24, at their outer sides, have 20 opening thereinto pipe inlets 42, these being extended without the furnace and a fluid supply may be connected to either of the same, it being understood, of course, that the one not connected to the fluid supply is 25 plugged in any suitable manner. Therefore, it may be seen that the fluid supply can be admitted through either end of the furnace at the option of the user thereof.

The front plate 14 of the furnace is provided with a swinging door 43 so that access 30 may be had to the chamber 23 for the cleaning of the latter or for repair purposes or to permit the assembling of the circulating unit or the knocking down thereof.

It is deemed needless to describe in detail 35 the working of the furnace in its entirety, because this should be obvious, and therefore a more extended explanation has been omitted.

40 What is claimed is:—

1. A furnace construction, comprising a lower body assembly forming a fire chamber and having an upper ledge, a superposed housing having separable ends, front, back 45 and top detachably connected with each other, the ends, front and back superimposed upon the lower body assembly, a fluid circulating unit within the housing including lower spaced connected drums, an upper 50 drum, tubes detachably connected with said drums for communication with each other, a plurality of coils detachably connected with the lower and upper drums and upwardly converging, baffles arranged on opposite sides 55 of the upper drum and saddle straps bridging said upper drum and forming hangers for the baffles, studs on the ends of the drums and engaged in the front and back of the housing, and means engaging the studs exteriorly of the housing.

2. A furnace construction, comprising a lower body assembly forming a fire chamber and having an upper ledge, a superposed housing having separable ends, front, back 65 and top detachably connected with each

other, the ends, front and back superimposed upon the lower body assembly, a fluid circulating unit within the housing including lower spaced connected drums, an upper drum, tubes detachably connected with said drums for communication with each other, a plurality of coils detachably connected with the lower and upper drums and upwardly converging, baffles arranged on opposite sides 75 of the upper drum, saddle straps bridging said upper drum and forming hangers for the baffles, studs on the ends of the drums and engaged in the front and back of the housing, and means engaging the studs without the housing, the said lower drums being 80 superimposed upon the said ledges.

3. A furnace construction, comprising a lower body assembly forming a fire chamber and having an upper ledge, a superposed housing having separable ends, front, back 85 and top detachably connected with each other, the ends, front and back superimposed upon the lower body assembly, a fluid circulating unit within the housing including lower spaced connected drums, an upper drum, tubes detachably connected with said drums for communication with each other, a plurality of coils detachably connected with the lower and upper drums and upwardly converging, baffles arranged on opposite sides of the upper drum, saddle straps bridging said upper drum and forming hangers for the baffles, studs on the ends of the drums and engaged in the front and back of the housing, and means engaging the studs, the said lower drums being 90 superimposed upon the said ledges, and means for admitting fluid to either of the lower drums.

In testimony whereof I affix my signature.

NATHANIEL G. HOLLAND.
